DESIGN FOR A SANITARY LAVATORY BRUSH CONTAINER

Arthur Illsche, Rye, N. Y.

Application August 27, 1936, Serial No. 64,595

Term of patent 7 years

To all whom it may concern:

Be it known that I, Arthur Illsche, a citizen of the United States and resident of Rye, in the county of Westchester and State of New York, have invented a new, original, and ornamental Design for a Sanitary Lavatory Brush Container, of which the following is a specification; reference being had to the accompanying drawing, forming part thereof.

In the drawing—

Fig. 1 is a view in perspective of a lavatory brush container embodying my ornamental design.

Fig. 2 is a top plan view thereof, and

Fig. 3 is a central, vertical section on the line s^3-s^3 of Fig. 2, looking in the direction of the arrows.

I claim:

The ornamental design for a sanitary lavatory brush container, as shown and described.

ARTHUR ILLSCHE.
